UNITED STATES PATENT OFFICE.

ROBERT SWITZER AND CLAIR T. LAMISON, OF RIMERSBURG, PENNSYLVANIA.

CHAIR FOR RAILROAD-JOINTS.

1,145,277.

Specification of Letters Patent.

Patented July 6, 1915.

Application filed October 3, 1914. Serial No. 864,918.

To all whom it may concern:

Be it known that we, ROBERT SWITZER and CLAIR T. LAMISON, citizens of the United States, residing at Rimersburg, in the county of Clarion and State of Pennsylvania, have invented certain new and useful Improvements in Chairs for Railroad-Joints, of which the following is a specification.

10 This invention relates to rail chairs for the meeting ends of railway rails, and aims to provide a chair of this character which will effectually support the meeting ends of the railway rails and prevent the same from working loose when subjected to the strain of rolling stock passing thereover.

15 An object of the invention is to provide a chair of this character which is simple in construction, cheap and easy to manufacture, and which is efficient in its operation.

20 Another object of the invention is to so construct the chair that the rail ends may be easily inserted therein without removing the rails from the ties.

25 With these and other objects in view, the invention consists in the novel features of construction and arrangement of parts as will be hereinafter more fully described, illustrated in the accompanying drawings, and then more specifically pointed out in the appended claims.

30 In the drawings: Figure 1 is a perspective view showing the meeting ends of a pair of railway rails with our improved chair applied thereto. Fig. 2 is a top plan view. Fig. 3 is an elevation of the inner end of the clamping member.

35 Referring to the drawings by numerals, R—R designates the meeting ends of a pair of railway rails, comprising the usual head 1, web 2 and base flanges 3. The chair comprises a base portion 4 on which the rail ends are adapted to rest and the extensions 5 and 6 for engagement with the sides of the rail. The extension 5 extends throughout the length of the chair and has its inner face so formed that it will snugly engage the under side of the head, the web, and the base flange 3 of the rail.

40 The extension 6 is of a similar construction as the extension 5 but does not extend throughout the length of the chair, a portion being cut away as shown at 7. A clamping block 8 is provided for sliding engagement with the cut out portion 7 and

is adapted to snugly engage the rail in a manner similar to the extension 5, a pin 9 being formed on or connected to the inner end of the block 8 for engagement with an opening 10 formed in the extensions 6 when the block 8 is inserted within the opening 7, a pin 11 then being inserted in an opening in the end of said pin 9 to lock the same and block 8 within the cut out portion of the extension 6. 65

45 In applying the device to a rail joint, the ends of the rails are positioned within the chair with their meeting ends approximately centrally thereof, the clamping block fitting into the cut out portion 7 with the pin 9 in engagement with the opening 10, and locked in such position by means of the pin 11.

50 From the foregoing description, taken in connection with the accompanying drawings, the advantages of the construction will be readily appreciated by those skilled in the art to which the invention appertains, and while we have described the principle of operation of the invention, together 75 with the device which we now consider to be the best embodiment thereof, we desire to have it understood that the device shown is merely illustrated, and that such changes may be made as are within the scope of the 80 85 claims.

We claim:—

1. A chair for the meeting ends of railway rails comprising a base portion having an extension on one side for engagement 90 with the rail webs, an extension on the opposite side for engagement with but one of the rail webs, and a block for clamping the second rail within said chair.

2. A chair for the meeting ends of rail- 95 way rails comprising a base portion having an extension on one side for engagement with the rail webs, an extension on the opposite side having a cut out portion and engageable with but one of the rail webs, a 100 block adapted to fit in said cut out portion and engage the second rail for clamping the rail to the chair, and means to lock said block in its clamping position.

3. A chair for the meeting ends of rail- 105 way rails comprising a base portion having an extension on one side for engagement with the rail webs, an extension on the opposite side for engagement with one of the rail webs, a block for clamping the second 110

rail within said chair, and a pin carried by said block and engageable with said chair to lock the block in its clamping position.

4. A chair for the meeting ends of rail-
5 way rails comprising a base portion having an extension on one side for engagement with the rail webs, an extension on the opposite side having an opening therein and adapted to engage but one of the rail webs,
10 a block for clamping the second rail within said chair, a pin carried by said block

and engageable with the opening in the second extension, and means to secure said pin within said opening to lock the block to the chair.

15

In testimony whereof we affix our signatures in presence of two witnesses.

ROBERT SWITZER.
CLAIR T. LAMISON.
